DESIGN FOR A SALT SHAKER

Willie Lewis Hickman, Tampa, Fla., assignor of one-half to William J. Trowell, Sulphur Springs, Fla.

Application November 28, 1941, Serial No. 104,374

Term of patent 3½ years

To all whom it may concern:

Be it known that I, Willie Lewis Hickman, a citizen of the United States, residing at Tampa, in the county of Hillsborough and State of Florida, have invented a new, original, and ornamental Design for a Salt Shaker, of which the following is a specification, reference being had to the accompanying drawing, forming part thereof.

I claim:

The ornamental design for a salt shaker, as shown.

WILLIE LEWIS HICKMAN.
